UNITED STATES PATENT OFFICE.

JULIUS LIBROWICZ, OF NEW YORK, N. Y.

DESIGN FOR A BOTTLE.

SPECIFICATION forming part of Design No. 22,137, dated January 17, 1893.

Application filed November 3, 1892. Serial No. 450,901. Term of patent 7 years.

To all whom it may concern:

Be it known that I, JULIUS LIBROWICZ, a citizen of the United States, residing at New York, county of New York, and State of New York, have originated and produced a Design for a Bottle; and I hereby declare the following to be a full, clear, and exact description of the same, reference being had to the accompanying drawings, forming part of this specification.

In the drawings Figure 1 is a perspective elevation of the bottle showing its exterior; and Fig. 2, a sectional elevation of the same taken approximately on the line $x-x$, Fig. 1, showing its contour in cross section.

The bottle generally has the appearance of a pillar, base and capital, and comprises the following essential features. The base 1 (from the exterior) is quadrangular in shape, the top 2 of which is convex; and the sides (or one or more of them) are provided with recesses 3, which may be used for the affixment of labels or other like matter. The pillar 4 extends between the cap 5, and the base 1, and is 25 trunco-pyramidal in form and has angular flutings 6 extending between the circular false base 7 and the circular false cap 8. The false cap has a series of segmental pro-

jections 9 surmounted by a series of intermittent blocks 10 which project from below 30 the cap 5. The front of the pillar 4 is provided with a recess 11, in which labels, &c. can be placed, the surface of the pillar at this point being flat. The cap 5 is circular peripherally and is provided with squared 35 sides 12 for the reception of labels, &c. Upon the cap 5 rests a cylindrical extension 13, the point of union of the extension and cap being defined by a rectangular boss 14 and a circular boss 15.

In cross section the bottle has much the same contour as the exterior, with the exception that surface ornamentation is not carried into the interior, and straight lines appear where the exterior discloses segmental 45 or irregular ones, except the bottom 16 which is convex.

I claim:

The design for a bottle, substantially as described and shown.

Signed at the city, county, and State of New York this 2d day of November, 1892.

JULIUS LIBROWICZ.
